Primary Examiner—Ruth McInroy
Attorney, Agent, or Firm—Rosenberg, Klein & Bilker[57] **CLAIM**

The ornamental design for a grill, as shown and described.

DESCRIPTION

FIG. 1 is a front, right and top view of a grill showing my new design;

FIG. 2 is a rear view thereof;

FIG. 3 is a front view thereof;

FIG. 4 is a right side elevational view, the left side being a mirror image thereof;

FIG. 5 is a top plan view thereof;

FIG. 6 is a bottom plan view thereof;

FIG. 7 is a right side elevational view thereof with the cover in an open position; and,

FIG. 8 is a right side elevational view of the grill thereof, the grill being shown separate for clarity of illustration.
